CLAIM

The ornamental design for a vehicle body, as shown and described.

DESCRIPTION

FIG. 1 is a left side view of a vehicle body showing our new design.

FIG. 2 is a right side view thereof.

FIG. 3 is a front view thereof.

FIG. 4 is a rear view thereof.

FIG. 5 is a front perspective view thereof; and,

FIG. 6 is a rear perspective view thereof.

It will be understood that the top is plain and unornamental and further that the hidden line shown throughout the drawings is for illustration only, forming no part of the claimed design.
